Samuel S. Hardy
his ATTORNEY

UNITED STATES PATENT OFFICE.

CHARLES VEYNE LOGWOOD, OF NEW YORK, N. Y., ASSIGNOR TO DE FOREST RADIO TELEPHONE AND TELEGRAPH COMPANY, OF NEW YORK, N. Y., A CORPORATION OF DELAWARE.

RADIO SIGNALING SYSTEM.

Application filed April 21, 1920. Serial No. 375,510.

To all whom it may concern:

Be it known that I, CHARLES V. Logwood, a citizen of the United States, residing at New York, county and State of New York, have made a certain new and useful Invention in Radio Signaling Systems, of which the following is a specification.

This invention relates to radio signaling systems, and more particularly to transmitting systems.

The object of the invention is to provide a transmitting system which is simple in circuit arrangement and efficient in operation.

15 A further object of the invention is to provide a radio signaling system wherein a source of high frequency oscillations is employed and the high frequency oscillations modulated in accordance with the signal to be sent, the circuits being so arranged that "overmodulation" is secured, i. e., the modulating signal current increases the power transmitted rather than decreases the same.

25 A further object of the invention is to provide a system of the character referred to particularly adapted for transmission of radio telephone messages where speech or audio frequency voice currents increase the power transmitted throughout the wave form thereof by the amount of modulation effected by the audio frequency voice current.

Further objects of the invention will appear more fully hereinafter.

The invention consists substantially in the construction, combination, location, and relative arrangement of parts, together with the circuit arrangement employed in connection therewith, all as will be more fully hereinafter set forth, as shown by the accompanying drawing, and finally pointed out in the appended claims.

Referring to the drawing, I employ a source of high voltage 1 which may be any suitable source, but which I have illustrated as a direct current dynamo. I do not desire

to be limited or restricted in this respect, however, as the circuit arrangement and the elements employed in connection therewith is to be regarded in the illustrative sense rather than in the limiting sense. The source of power 1, however, has two distributing circuits, one of which passes from the source 1 through the choke coil 2 to wire 3, ammeter 4, coil 5, inductance coil 6, to the plate electrode 7 of oscillion 8, which for the purpose of my invention has been illustrated as being of the evacuated tube type, having located therein filament, grid and plate electrodes of the usual construction, but I do not desire to be limited in this respect as any vessel having associated therewith a hot and two or more cold electrodes each located at a relatively different distance from the hot electrode and adapted to be a source of high frequency oscillations, may be employed. The current path being described from the source 1 passes from the plate 7 through the space of the oscillion 8, in the arrangement shown, to the filament electrode 9, and from there to the negative side of the source 1. The other path of current from the source 1 is through the choke coil 2 to wire 10, ammeter 11, coil 12, choke coil 13, to plate electrode 14 of the oscillion 15, and thence to the filament electrode 16 of the oscillion 15 and through to the negative side of the current source 1 as before. The current also has a path from the coil 12, wire 17, through coil 18, wire 19, coil 20, choke coil 6, and plate electrode 7 of the oscillion 8, across to the filament 9 thereof, and back to the negative side of the current source 1. Similarly, there is a wire connection 21 from the coil 5, which connects with one terminal of the coil 20 through wire 19, one terminal of the coil 18, wire 17, through choke coil 13 to the plate electrode 14 of the oscillion 15, thence to the filament 16 thereof, back to the negative side of the current source 1. An additional circuit path is provided

from the wire 19 to the positive terminal of a condenser 22, the negative terminal of which is connected to the negative terminal of a condenser 23, the positive of which is connected to the filament electrodes 16 and 9 of the respective oscillations 15 and 8. The filaments 16 and 9 of the oscillations are lighted in the usual well known manner, for example, by means of a current source 24, as will be readily apparent. When the circuit above described is connected to an oscillating circuit which may be traced from the plate electrode 14 through wire 24, condenser 25, inductance 26, condenser 27, ammeter 28 to earth 29, and similarly from the plate electrode 7, through wire 30 to the antenna earth circuit (the antenna of which is illustrated at 31), there is obtained a definite output of continuous high frequency current. The coils 20, 12, 5 and 18 are all wound on a common iron core, the coils 12 and 5, however, being wound oppositely so as to cause an opposed magnetic circuit through the iron core 33 common to all of the coils. The grid electrodes 34 and 35 of the oscillations 15 and 8 respectively are connected to each other through coils 36 and a common inductance coil 37 which is inductively associated with the signaling device, which may be either a microphone 38 included in circuit with the telephone coil 39, and a current source 40, or may be a signaling key 41 as shown. I preferably connect the inductance coil 37 which in the form shown is the secondary of an audio frequency transformer to the negative side of the current source 1, the same being controlled by a key 42 connected in series with the high resistance 43. When, for example, the key 41 is closed a strong positive charge is imposed upon the grid electrode 34 of oscillation 15. There is also a strong negative charge on grid electrode 35. This has such an influence on the grid electrode 35 of the oscillation 8 that it almost stops the flow of current from the plate electrode 7 of oscillation 8 to the filament electrode 9 thereof. When any circuit is suddenly robbed of its current the potential begins to rise to a high value, and in this case it has a path through the coil 20 in a clockwise direction which passes into the condenser 22, and also through coil 18 to plate electrode 14 of oscillation 15 passing through the coil 18 in a clockwise direction. At this instant, the fields of the coils 12 and 5 are no longer in opposition, due to the stopping of the current in the coil 5, as above described, on the plate electrode 7. Thus a strong magnetic field is built up in the coil 12. This causes a rush of induced current through the coils 20 and 18. The current in the coil 20 is not strong because the flow would be to the plate electrode 7 of oscillation 8, which has already been stopped by

a negative charge on the grid electrode 35 of oscillation 8, while the current in the coil 18 passes into the condenser 22, condenser 23, to the filament electrodes of the oscillation, thereby making the plate electrode 14 of oscillation 15 negative and the filament 16 thereof positive. This would tend to stop the current flowing from the current source 1 to the line 10 by making the plate electrode 14 negative. After the current in this branch (current source 1, line 10, coil 12, etc.) has been stopped flowing across the space between the plate and filament electrodes 14, 16, then the potential would rise and pass through the coil 12, coil 18, into the condenser 22, at the same time the imposed E. M. F. on the coil 5 would prevent any flow through the coil 20, coil 6, to the plate electrode 7 of oscillation 8. At this point the grid charge leaks off through the resistance 43 to the filament electrodes allowing currents to flow from plates 14 and 7 to the filaments 16 and 9 respectively, thus restoring the circuit to its normal oscillating condition, but the condenser 22 has held an excessive potential, and after the grid starts leaking off the charge this condenser discharges into the plate electrodes 14 and 7 again, through the coils 20 and 18, as will be apparent, thus adding to the high potential of the current source 1. This causes momentarily an excessive rate of oscillating currents due to the actions of the grids 34 and 35 such as interrupting current in the primary circuit of the grids 34 and 35 of the oscillations 15 and 8, and provide an adjustable tap connection 52 between the condensers and inductance 26. The condensers 27 can be from .0004 to .009 mf. While the condensers 22 and 23 are comparatively larger, for example, about from one to two mf, I shunt the terminals of the current source 1 with a condenser 55, which is provided to smooth out the commutator ripples. The coils 13, 6, and 36, are preferably air core choke coils which are provided to prevent high frequency currents from getting back into the circuit parts. With the arrangement thus described I have found that the operation is as above set forth. When the grid electrode 35 becomes negative it stops the current to a certain extent from the current source 1, line 3, coil 5, while the grid 34 of oscillation 15 is positive to a certain extent, but the increase of positive potential on the grid 34 does not greatly increase the flux in the circuit from the current source 1, line 10, and coil 12, and in consequence the induced current in the coils of the common core 33 is so great that it overpowers the effect of increased positive

potential on the grid 34 relative to the plate electrode 7 and causes the induced current in the coil to make the plate electrode 14 very negative, thereby stopping the current 5 as much as the grid electrode 35 has stopped the current in the coil 5 and prevented same from reaching the filaments 16 and 9. When 10 two indicating current meters, such as is illustrated at 11 and 4, are put in the circuits shown and the Morse key 41 or the microphone 38 is operated the current drops in both of the oscillating audions or oscillations 15 and 8 at the same time. This causes a falling off of any radiating energy 15 in accordance to the number of times the grid electrodes 34 and 35 of the respective oscillations become negatively and positively charged. When the current in the plate electrodes 14 and 7 have been stopped by 20 grid potential changes the rising in potential throughout the circuit from the current source 1 will charge the condenser 22 to an excessive potential, and it will discharge back into the plate electrodes 14 and 7 only 25 when the grid electrodes 34 and 35 cease to act on the plate electrodes 14 and 7 respectively. When the condenser 22 discharges it actually increases the rate of radiation above normal radiation so that at 30 the end of each impulse from the grid system this discharge from the condenser assists and adds potential to the current source 1. In other words, when the signals are being sent the amount of the charge of the 35 condenser 22 is added to the normal power generated by the system, and through the operation above described the system instantly restores itself to normal radiation condition when no modulation is taking 40 place, i. e., no signals are being sent. From the foregoing it will be seen that I have provided a system which may briefly be summed up by the statement that when signals are being transmitted the power radiated is 45 greater than normal rather than less than normal as is the case of transmitting systems heretofore proposed.

Many modifications and changes in detail will readily occur to those skilled in the 50 art without departing from the spirit and scope of my invention as defined in the claims, therefore what I claim as new and useful and of my own invention and desire to secure by Letters Patent is,—

55 1. In an electrical signaling system, means for generating oscillating currents, and means for modulating the oscillating currents by and in accordance with the signals to be transmitted, means for interrupting current and means for increasing the strength of the transmitted currents by the modulation of the oscillating currents.

60 2. In an electrical signaling system, means for generating and transmitting high frequency oscillations, means for modulating

the oscillations by and in accordance with the signals to be transmitted, means for interrupting current and means for increasing the strength of the transmitted waves by the modulation of the oscillating currents. 70

3. In a radio signaling system, a source of high frequency currents, a source of low potential signal currents for modulating the high frequency currents by and in accordance with the signals to be transmitted, means for interrupting currents and means for increasing the strength of the transmitted waves during the modulation of the high frequency currents. 75

4. In an electrical signaling system, means for generating oscillating currents, and means for modulating the oscillating currents by and in accordance with the signals to be transmitted, means for interrupting current and means for increasing the strength of the transmitted currents by and in proportion to the modulation of the oscillating currents. 80

5. In an electrical signaling system, means for generating and transmitting high frequency oscillations, means for modulating the oscillations by and in accordance with the signals to be transmitted, means for interrupting current and means for increasing the strength of the transmitted waves by and in proportion to the modulation of the oscillating currents. 90

6. In a radio signaling system, a source of high frequency currents, a source of low potential signal currents for modulating the high frequency currents by and in accordance with the signals to be transmitted, means for interrupting current and means for increasing the strength of the transmitted waves during the modulation of the high frequency currents, and proportionally to the low potential signal currents. 100

7. In a modulating system, and in combination with a source of high frequency oscillations and signal controlled means for modulating the same, of means for increasing the strength of the oscillations by and during the modulation thereof. 110

8. In a modulating system, and in combination with a source of high frequency oscillations and signal controlled means for modulating the same, of means controlled solely by the signals to be transmitted for increasing the strength of the oscillations 115 during the modulation thereof.

9. In a modulating system, and in combination with a source of high frequency oscillations and signal controlled means for modulating the same, of means actuated by the signals to be transmitted for increasing the strength of the oscillations during the modulation thereof. 125

10. In a modulating system, and in combination with a transmitting system and a 130

- source of high frequency oscillations having at least two paths controlled by electron discharge, of means for stopping the flow of current through one path, means controlled thereby for building up and storing energy, and means for adding the energy stored up to the energy supplied said transmitting system.
11. In a modulating system, and in combination with a transmitting system and a source of high frequency oscillations having at least two paths controlled by electron discharge, of means controlled by the signals to be transmitted, for stopping the flow of current through one path, means controlled thereby for building up and storing energy, and means for adding the energy stored up to the energy supplied said transmitting system.
12. In a modulating system, and in combination with a transmitting system and a source of oscillations having at least two paths therefor to said transmitting system, of means for stopping the flow of current through one of said paths, means controlled thereby for building up and storing energy, and means for adding the stored energy to the energy supplied said transmitting system.
13. In a modulating system, and in combination with a transmitting system and a source of oscillations having at least two paths therefor to said transmitting system, of means controlled by the signals to be transmitted, for stopping the flow of current through one path, means controlled thereby for building up and storing energy, and means for adding the energy stored up to the energy supplied said transmitting system.
14. In a modulating system, and in combination with a transmitting system and a source of high frequency oscillations having at least two paths controlled by electron discharge, of means for stopping the flow of current through one path, means controlled thereby for building up and storing energy and means for adding the energy stored up to the energy supplied said transmitting system, and means for restoring said system to its normal condition upon cessation of signals to be transmitted.
15. In a modulating system, and in combination with a transmitting system and a source of high frequency oscillations having at least two paths controlled by electron discharge, of means controlled by the signals to be transmitted, for stopping the flow of current through one path, means controlled thereby for building up and storing energy, and means for adding the energy stored up to the energy supplied said transmitting system, and means for restoring said system to its normal condition upon cessation of signals to be transmitted.
16. In a modulating system, and in combination with a transmitting system and a source of oscillations having at least two paths therefor to said transmitting system, of means for stopping the flow of current through one of said paths, means controlled thereby for building up and storing energy, and means for adding the stored energy to the energy supplied said transmitting system, and means for restoring said system to its normal condition upon cessation of signals to be transmitted.
17. In a modulating system, and in combination with a transmitting system and a source of oscillations having at least two paths therefor to said transmitting system, of means controlled by the signals to be transmitted, for stopping the flow of current through one path, means controlled thereby for building up and storing energy, and means for adding the energy stored up to the energy supplied said transmitting system, and means for restoring said system to its normal condition upon cessation of signals to be transmitted.
18. The combination with an antenna, of means for generating and supplying oscillating currents to said antenna including a cathode, grid and plate electrodes, a source of current for said plate electrodes, means temporarily stopping the flow of current from one of said plate electrodes to the cathode, means rendered effective thereby for building up and storing energy, and means for supplying the stored energy to the antenna additively to the normal supply of energy thereto.
19. The combination with an antenna, of means for generating and supplying oscillating currents to said antenna including a cathode, grid and plate electrodes, a source of current for said plate electrodes, means for charging said grid electrodes with opposite potentials, means controlled thereby for building up and storing energy, and means for supplying the stored energy to the antenna additively to the normal supply of energy thereto.
20. The combination with an antenna, of means for generating and supplying oscillating currents to said antenna including a cathode, grid and plate electrodes, a source of current for said plate electrodes, means temporarily stopping the flow of current from one of said plate electrodes to the cathode, means rendered effective thereby for building up and storing energy, and means for supplying the stored energy to the antenna additively to the normal supply of energy thereto during the modulation of the oscillating currents by and in accordance with the signals to be transmitted.
21. The combination with an antenna, of means for generating and supplying oscillating currents to said antenna, including

a cathode, grid and plate electrodes, a source of current for said plate electrodes, means for charging said grid electrodes with opposite potentials, means controlled thereby for building up and storing energy, and means for supplying the stored energy to the antenna additively to the normal supply

of energy thereto during the modulation of the oscillating currents by and in accordance with the signals to be transmitted. 10

In testimony whereof I have hereunto set my hand on this 14th day of April, A. D. 1920.

CHARLES VEYNE LOGWOOD.
